UNITED STATES PATENT OFFICE.

NELSON S. BOWDISH, OF RICHFIELD SPRINGS, NEW YORK.

IMPROVEMENT IN PHOTOGRAPHIC POSING-CHAIRS.

Specification forming part of Letters Patent No. 120,485, dated October 31, 1871.

To all whom it may concern:

Be it known that I, NELSON S. BOWDISH, of Richfield Springs, in the county of Otsego and State of New York, have invented an Improvement in Photographic Posing-Chairs; and the following is declared to be a correct description of the same.

This chair is provided with a swinging arm, attached to the metallic frame of the chair-bottom, and carrying the head-rest, so as to dispense with the separate stands heretofore employed, and a semicircular back is constructed with a segmental support that allows the back to be placed in any desired position relatively to the front of the chair.

In the drawing, Figure 1 is a plan of the chair, with the back and cushion removed. Fig. 2 is a vertical section of the chair and back. Fig. 3 is an inverted plan of the semicircular back; and Fig. 4 is a side view of a nearly-straight back that may be employed in place of the semicircular back.

The open metallic frame *a* forms the body of the chair, and to this the legs *b*, sides *c*, and front *d* are attached, said frame being made with a vertical flange or rim, to which the wood-work is screwed. In this manner the chair is made very strong, and at the same time it can be ornamented to any desired extent. Beneath the frame *a* is an arm, *e*, that is attached by a screw, 2, and has a lip, 3, and clamping-screw, acting with the segment 4 of the frame *a*, to hold said arm *e* firmly in any position into which it may be swung horizontally. At the end of this arm *e* is the socket and clamp *f* for the head-rest *g*, so that this arm *e* holds the head-rest in a very firm manner as a part of the posing-chair, thereby dispensing with the separate head-rest stands heretofore usually employed. I remark that this arm *e* may be made in two parts, so that it may be lengthened or shortened to bring the socket *f* and head-rest *g* nearer to or further from the person sitting in or standing near said chair. The head-rest is to be constructed in any convenient manner. I have shown a second slide-tube, 5, and horizontal rod 6, secured by clamps; and this head-rest might be made to carry a movable back-rest, to take the place of the chair-back. The cushion or seat *k* of the chair may be of any desired character. The back legs *b* are extended above the frame *a*, and provided

with metallic slides *i i*. It is preferable to make these slides *i* a part of the frame *a*, or to connect them firmly. The slides *i* receive the vertical bars *l l*, which are connected by a metallic segment, *n*, upon which rests the semicircular or segmental back *m*; and these parts are connected by a curved flange, *o*, secured to the under side of the back *m*, and taking beneath the edge of the segment *n*. By this means the chair-back can be placed at any desired height from the seat, and held by the clamp-screws 16; and the back can be moved upon the segment *n* so as to occupy any required position relatively to the front or sides of the chair. Movable arm-pieces *r* are provided between the upper parts of the back legs *b* and the sides *c c*, and these arms *r* are secured by hooks on the arms passing into eyes 7 upon the parts *b*, and a bolt or pin at the front end of the arm passes into a hole in the top of the front leg. By this construction of posing-chair the arms can either be employed or removed, as desired, and the back turned around to accommodate the sitter. As an additional convenience I make a back, shown in Fig. 4, which may be inserted in the slides *i* and raised or lowered as required; and this chair-back can be used for leaning against while the subject is standing, or as a support in sitting.

I claim as my invention—

1. The photographic posing-chair made with a metal frame, *a*, to which the wooden legs *b*, sides *c*, and front *d* are attached, as set forth.

2. The arm *e*, attached to the under side of the frame *a*, and carrying the adjustable head-rest, in combination with the segment 4, lip 3, and clamp, substantially as and for the purposes specified.

3. The segmental back supported by and movable upon the bars *l*, and segment *n*, in combination with the slides *i*, as and for the purposes set forth.

4. The movable arms *r*, connected when in place by the eyes 7, and hooks to the upper parts of the back legs of the posing-chair, as and for the purposes set forth.

Signed by me this 5th day of June, A.D. 1871.
NELSON S. BOWDISH.
